US0D1052698S

(12) **United States Design Patent** (10) Patent No.: **US D1,052,698 S**
(45) Date of Patent: ** Nov. 26, 2024

(54) **FLUID COUPLING**

(71) Applicant: **Colder Products Company**, Roseville, MN (US)

(72) Inventors: **Yogesh Mohan Bhat**, Bengaluru (IN); **Junxiao Chen**, Suzhou (CN); **Elizabeth J. Langer**, Minneapolis, MN (US); **Sanidhya Kumar Sanu**, Bangalore (IN); **Grant A. Wilhelm**, Plymouth, MN (US); **Xin Zhang**, Sushou New District (CN)

(73) Assignee: **Colder Products Company**, Roseville, MN (US)

(**) Term: **15 Years**

(21) Appl. No.: **29/806,977**

(22) Filed: **Sep. 8, 2021**

Related U.S. Application Data

(63) Continuation of application No. 17/406,651, filed on Aug. 19, 2021, now Pat. No. 11,566,738.

(57) **CLAIM**

The ornamental design for a fluid coupling as shown and described.

DESCRIPTION

FIG. 1 is a first perspective view of the fluid coupling.

FIG. 2 is a first side view of the fluid coupling.

FIG. 3 is a second side view of the fluid coupling.

FIG. 4 is a third side view of the fluid coupling.

FIG. 5 is a fourth side view of the fluid coupling.

FIG. 6 is a top view of the fluid coupling; and,

FIG. 7 is a bottom view of the fluid coupling.

The dashed broken lines illustrate portions of the fluid coupling that form no part of the claim.
